UNITED STATES PATENT OFFICE.

MAGNUS UNGER, OF PITTSFIELD, MASSACHUSETTS, ASSIGNOR TO GENERAL ELECTRIC COMPANY, A CORPORATION OF NEW YORK.

FURNACE CRUCIBLE.

Application filed April 18, 1922. Serial No. 554,577.

The present invention comprises a new refractory container or crucible which is particularly well adapted for induction furnaces.

5 Heretofore, furnace crucibles, particularly when providing channels for the circulation of charge, have been constructed by tamping the refractory material in a comminuted state mixed with a binder in a mold 10 containing a core which could be removed by fusion or combustion. This method of construction required time-consuming drying and baking of large masses to which the air had little or no access and which could 15 not readily be handled or transported.

In accordance with my invention I have provided a crucible consisting of a plurality of preformed members which are adapted to be assembled in telescoping relation in proper position with respect to the other parts of 20 the furnace. These members can be made and kept in reserve in any quantity, and when assembled permit of the immediate resumption of furnace operation. The novel 25 features of my invention will be pointed out with particularity in the appended claims.

I have illustrated in the accompanying drawings two embodiments of my invention constituted by crucibles for induction furnaces each of which is provided with a main reservoir and a communicating channel in 30 which the charge is subjected to heating by induced currents.

Fig. 1 of the drawings is a vertical section 35 of an induction furnace containing a crucible constructed in accordance with my invention; Fig. 2 is a vertical section of the crucible with the members partly disengaged; Figs. 3 and 4, respectively, represent a vertical section and a plan view of an 40 assembled crucible; Figs. 5 and 6, respectively, constitute an elevation and a vertical section of a modification.

A substantially complete induction furnace has been shown in Fig. 1 to make plain 45 the relation of the various parts. The furnace comprises a magnetic core 1 upon which is mounted a primary winding 2. The secondary is constituted by the charge 50 contained within a cylindrical channel 3 surrounding the core 1 and axially displaced with respect to the primary winding 2, thereby causing by electromagnetic repulsion 55 a circulation of molten charge between the channel 3 and the reservoir 4 through

the conduits 5, 6. This arrangement of the primary and secondary windings constitutes no part of my present invention. Fig. 1 also for the sake of completeness shows a cover 7, a charging door 8 and a spout 9, 60 but these are parts with which my invention is not concerned. A heat insulating layer 10 has been diagrammatically indicated.

The furnace body or crucible, as best shown in Figs. 2 and 3, comprises tubular 65 members 11, 12 adapted to be nested to provide a hollow frame or looped channel and also a pot or reservoir 13 adapted to engage 70 with the channel with its major axis at right angles to the major axis of the members 11, 75 12. The member 12 is provided with a recess 14 and a flange 15 upon the interior surface located respectively at opposite ends. 80 The member 11 has a corresponding flange 16 and a recess 17 on the exterior surface at 85 opposite ends. When the members 11, 12 are nested so as to cause the flange 16 to engage with the recess 14 and the flange 15 with the recess 17 a strong compact structure is produced. The members 11, 12 and 13 may consist of fire brick, or other suitable 90 refractory material, and are molded and fired by the usual methods. As best shown at in Figs. 3 and 4, the upper surface of the member 12 is recessed to receive the reservoir 13, the joint being cemented upon assembly as indicated at 18.

A preferred method of cementing the parts of a crucible consisting of fire brick is carried out as follows: A quantity of fire 95 clay or cement rendered plastic by water is introduced at the shoulder or angle of the joint. The parts to be cemented are brought together. Into the space remaining between the parts, as for example, the space remaining 100 between the cylindrical members 11 and 12, dry particles of burnt fire brick are introduced which mix with the plastic clay absorbing a large part of the moisture. I prefer to use particles passing $\frac{1}{8}$ to $\frac{1}{4}$ inch 105 mesh screen. These particles are rammed in firmly and the joint then may be fired immediately. This method avoids cracking and honey-combing of the cement and results in a substantially homogeneous crucible.

Fig. 1 shows at 19 an external clamp for one part of the joint where no shoulder has been provided to insure that no leakage of 110 charge should occur. As shown in Figs. 5

and 6 the clamp may be constituted by steel straps held together by steel bolts 20. Other and additional clamping means may of course be employed.

5. Figs. 5 and 6 illustrate a crucible for an induction furnace in which the members 22, 23 are telescopically jointed to provide a looped channel which communicates at opposite ends with the space within the reservoir 24. An external clamp has been provided as in the crucible shown in Fig. 1.

A furnace crucible constituted of pre-formed, interlocking or jointed units may be made of refractory material having properties best suited for the desired service without reference to their adaptability to tampering into a mold, extra parts properly fired may be kept in stock so that in case of a break in the crucible repairs may be made promptly.

What I claim as new and desire to secure by Letters Patent of the United States, is:—

1. An electric furnace crucible comprising a plurality of members which when 25 nested are in contact at separated regions and being shaped to provide a looped channel intermediate said regions of contact.

2. An induction furnace crucible comprising members consisting or preformed refractory material, said members being engageable with one another to provide a channel which is closed upon itself.

3. An induction furnace crucible comprising separable refractory members which 35 when in engagement provide a hollow, annular body having inlet and outlet openings.

4. An electric induction furnace crucible comprising a plurality of preformed mem-

bers telescopically joined with one another 40 but otherwise spaced apart to provide a channel.

5. An induction furnace crucible comprising a plurality of nested cylindrical members joined at their peripheries but 45 otherwise separated by a space which provides a charge-receiving channel, and a container fitted to said members and communicating with said channel.

6. An induction furnace crucible comprising a plurality of nested cylindrical members, the inner periphery of one member being sealed to the outer periphery of the other member at opposite ends, said members otherwise being separated by a 55 space, a third cylindrical member fitted to the side wall of the outermost of said nested members and conduits connecting the space between said nested members with the space within said cylindrical member. 60

7. An induction furnace crucible comprising a cylinder of refractory material having a recess and a flange respectively at opposite ends on the interior surface, a second cylinder having a recess and a flange 65 respectively upon the exterior surface, the flange of one cylinder engaging with the recess of another cylinder spacing apart said cylinders to provide an annular charge-receiving channel, and a third cylinder engaging with said first-named cylinder with the major axis at right angles to the major axis of said nested cylinders, and communicating with said annular charge-receiving channel. 70 75

In witness whereof, I have hereunto set my hand this 17th day of April, 1922.

MAGNUS UNGER.
